ASTRONOMIC DIAL FOR TIME SWITCHES

Frederick C. Holtz, Springfield, Ill., assignor to
 Sangamo Electric Company, Springfield, Ill., a
 corporation of Illinois

Application May 12, 1933, Serial No. 670,704

11 Claims. (Cl. 200—38)

The present invention relates to astronomic dials for time switches and the like, such as have the utility of turning on and off electric signs, electric lights, etc., according to the rising and setting of the sun. In their general construction, devices of this type comprise a dial head which is rotated by a suitable clock or other timing mechanism at a speed such that the dial head makes one complete revolution every twenty-four hours. The electrical switch which is associated with this dial head is actuated by two switch actuators in the form of knobs, studs or the like, which project from the dial head at spaced points and are adapted to engage the switch tripping parts. One such switch actuator closes the electric switch, as at sunset, and the other switch actuator opens the electric switch, as at sunrise. These two switch actuators are carried by the dial head to revolve therewith, and are also capable of shifting movement in angular paths concentric of the dial head, whereby they may be advanced or retarded with reference to the hour marks or other datum points on the dial head. For a given day of the year at a given latitude, these two switch actuators will occupy certain positions with respect to the hour marks or datum points on the dial head. With the change of the seasons, said switch actuators will be moved with an advancing or recessional movement relatively to the aforesaid positions, with the change in time of sunrise and sunset. This automatic shifting of the positions of the switch actuators is effected by cams which are mounted within the dial head and are carried thereby, but which are arranged to have a relatively slow rotative movement with respect to the rotating dial head.

One of the principal objects of the invention is to provide improved motion transmitting mechanism for transmitting motion from the cams to the switch actuators, i. e., shifting the angular positions of the switch actuators relatively to the dial head in accordance with the change of angular position of the cams relatively to the dial head. Each switch actuator is secured to the outer end of a swinging arm which is preferably mounted for oscillation about the hub of the dial head. Associated with each cam is a cam follower which is caused to move inwardly and outwardly in following the different radii of the cam. One of the specific features of improvement of my invention resides in the manner of transmitting motion from the cam follower to said swinging arm. This is done by a gear sector and pinion, the gear sector preferably

constituting an extension of the cam follower, and the pinion being secured to the hub of the swinging arm. The sector and pinion connection insures that the movement transmitted from the cam follower to the switch actuator shall be at a constant ratio throughout the entire range of movement of the follower and switch actuator. This is advantageous over the use of a link connection between the cam follower and swinging arm, where the shifting of the pivot centers of the connecting link, particularly adjacent to the limits of movement of the switch actuator, is likely to change the ratio of the movement transmitted from the cam follower to the switch actuator. Where a high degree of accuracy of timing control is desired, this variation of the ratio of movement must be compensated for by a corresponding variation in the contour of the cam, which complicates the matter of properly shaping the cam. In the present construction, where a constant ratio of movement is obtained by the sector and pinion arrangement, this is avoided and the only consideration in the proper shaping of the cam is the seasonal change of sunrise and sunset corresponding to the latitude in which the instrument is used.

The sector and pinion construction is also advantageous in simplifying the assembly of the device, and in providing a construction which is simple and inexpensive to manufacture.

Another object of the invention is to provide an improved construction in which the cams are readily accessible, so that they can be interchanged with facility in adapting the device to use in different latitudes or under different operating conditions.

Another object of the invention is to provide a construction including an improved arrangement of guide means for guiding the motion of the swinging arms which carry the switch actuators.

Other objects and advantages of the invention will appear from the following detail description of a preferred embodiment of the invention. This embodiment is disclosed as for the purpose of performing switching operations in accordance with the rising and setting of the sun, but it will be understood that the invention is not necessarily restricted to such use, as the timed intervals or schedule may be changed to agree with any other predetermined arrangement for a calendar year.

In the accompanying drawings:—

Figure 1 is a front elevational view of the improved dial embodying my invention, this view

illustrating, diagrammatically, certain switch parts to be actuated by the dial;

Figure 2 is a side or edge elevational view, as viewed from the bottom of Figure 1;

5 Figure 3 is a transverse sectional view, corresponding to a section taken approximately on the plane of the line 3—3 of Figure 4;

10 Figure 4 is an axial sectional view taken approximately on the plane of the line 4—4 of Figure 3;

15 Figure 5 is a detail perspective view illustrating the sector and pinion arrangement of motion transmitting mechanism operative between each cam and the swinging arm bearing the associated switch actuator;

Figure 6 is a perspective view of the cam assembly; and

20 Figure 7 is a detail perspective view of one of the swinging arms with the pinion secured thereto.

The dial head is designated 11 in its entirety, and the "On" and "Off" switch actuators are designated 12 and 13, respectively. These two switch actuators are disposed in different trans-

25 verse planes of the dial head, as shown in Figure 2. The switch assembly, designated 14, may be of any desired construction. In the exemplary construction illustrated is a diagrammatic representation of the general type disclosed in the co-

30 pending application of Wilmeth and Keyes, Serial No. 616,180, filed June 9, 1932. Briefly de-

35 scribed, these switch parts comprise the stationary contact 15, the movable contact 16, and the three switch tripping levers 17, 18 and 19. The

35 lever 19 carries a roller 20 which, in one movement of said lever, is adapted to press the switch contacts apart. The lever 17 comprises an ex-

40 tension arm 17a carrying a pivot pin 17b, and the lever 18 is pivotally mounted on said pin.

45 The lever 18 comprises an extension arm 18a, and the lever 19 comprises an extension arm 19a, and extending between these extension arms is a tension spring 21. A shoulder 19b on the ex-

45 tension arm 19a is adapted to engage a shoulder 18b on the lever 18 when the switch is in closed position. The spring 21 tends to swing the arm 19 into a switch opening position, which is per-

50 mitted when the arm 18 is actuated to draw its shoulder 18b out from in back of the shoulder 19b on the lever 19. The lever 17 is in the path

55 of the switch actuator 12, and the lever 18 is in the path of the switch actuator 13, whereby these levers are engaged successively by the

60 switch actuators in the rotation of the dial head 11. In the switch closing operation, the actuator 12 engages the lever 17 and swings it to carry the lever 18 outwardly for restoring the shoulder 18b in position to engage the shoulder 19b. When the lever 17 snaps off the actuator 12, it is drawn

65 back by a spring 23 against a stop 24, such motion acting through the lever 18 and shoulders 18b, 19b to oscillate the lever 18 back to switch closing position. In the switch opening operation, the engagement of the actuator 13 against

70 the lever 18 draws the shoulder 18b out from be-

75 hind the shoulder 19b, permitting the spring 21 to oscillate the lever 18 to switch opening position. It will be understood that any other type of switch may be used, the above described

70 switch being shown merely for illustrative purposes.

Referring to Figure 4, the dial head is secured to a rotating shaft 25 which is driven by a clock train or any other suitable timing mechanism.

75 This shaft is arranged to rotate exactly one revo-

lution every twenty-four hours. The dial head comprises a main circular mounting plate 26, to the outer face of which is detachably secured a marked disc 27. The face of this disc has inscribed thereon the numbered markings 27a designating the 24 hours of the day, preferably subdivided into fifteen minute intervals, and also has inscribed thereon the "Day" and "Night" marks 27b, the directional arrow 27c, and the latitude marking 27d. Cut through this face disc 10 and through the mounting plate 26 is a sight window 28 through which the indications on the month wheel can be viewed. Two screws 29 pass through openings in the marked disc 27 and thread into the mounting plate 26 for fixedly 15 securing the disc to the plate. The mounting plate is secured to a hub 31 which fits over the drive shaft 25, the rear end of said hub abutting against a shoulder 25a on the drive shaft. Any suitable retaining device 32, such as a transverse 20 pin or nut, coacts between the front end of the hub 31 and said shaft for retaining the dial head on the shaft, the operative connection being such as to compel rotation of the dial head with the shaft. The back side of the mounting plate 25 26 abuts against the shoulder 31a on the hub 31, and this mounting plate, together with the disc 27, are clamped between said shoulder and a nut 33 which screws inwardly over the threaded outer end of the hub. A suitable set screw 34 30 may be provided for holding the nut 33 in its tightened position. In the event that the cam assembly is changed for a different latitude, the marked disc 27 can be substituted with another disc having the proper latitude marking 27d by 35 merely removing the screws 29 and nut 33, whereupon the disc 27 may be lifted off the mounting plate 26 and a new disc substituted.

Referring to Figure 3, four spacing studs or

40 posts 36, 37, 38 and 39 have their front ends riveted in the mounting plate 26 and project rearwardly therefrom, these posts being ar-

45 ranged in pairs. Screws 36a, 37a, etc., thread into the outer ends of these posts (see screw 31a in Figure 4) and secure spacing sleeves and other 50 parts of the assembly on these posts. An ar-

45 cuate bridge bar 41 is secured to the outer ends of one pair of posts 36, 37, and a similar arculate bridge bar 42 is secured to the outer ends of the 55 other pair of posts 38, 39. A pintle 43 for the two cam followers is supported between the 50 mounting plate 26 and the bridge bar 41, and a pintle 44 for the star wheel (to be later de-

55 scribed) is secured between the mounting plate 26 and the other bridge bar 42. As will be later described, other pairs of arculate bars extend be-

70 tween these posts for defining guide-ways for the swinging arms that support the switch actuators.

The month wheel 46 is rotatably mounted di- 80 rectly in back of the plate 26 and disc 27, where the month indicia 46a inscribed on this wheel can be viewed through the sight window 28. Preferably, the month intervals are subdivided into five-day intervals, with the month inter- 85 vals of varying angular extent corresponding to the different lengths of the months. These in- dicia 46a cooperate with an index pointer 28a fixedly secured in the sight window 28. The peri-

70 phery of the month wheel 46 is provided with 70 gear teeth 46b which mesh with a driving pinion 47. This pinion is secured to a pintle 48 which has its front end journaled in the mounting plate 26. A large spur gear 49 is also secured to the 75 pintle and drives the pinion 47. A light spring 75

arm 51 is secured to the adjacent mounting post 38 and has its resilient end bearing against the spur gear 49 for holding the front end of the pintle 48 in its bearing in the mounting plate 26. Meshing with the large gear wheel 49 is a spur pinion 52 which is secured to the pintle 48. A five-pronged star wheel 53 is secured fast to the rear end of this pintle, beyond the bridge bar 42. The arms or fingers of this star wheel project from the periphery of the dial head, in position to engage with a stationary pin 54 which is fixedly secured to any stationary mounting structure adjacent to the dial head. In each revolution of the dial head, occurring once in 24 hours, one of the fingers of this star wheel is engaged by the pin 54 and the wheel is rotated clockwise with respect to the dial head, which is rotating counterclockwise, as viewed in Figure 1. The pin 54 is disposed so that it has no interference with the switch actuators 12, 13 or with the swinging arms supporting the latter. Rotating with the star wheel is a pentagonal detent boss 55 against which the free end of a leaf spring 56 bears for yieldingly holding the star wheel and its pinion 52 in each of its advanced positions. The leaf spring 56 is coiled about the spacing post 38 and is pressed inwardly by a pin 57. It will be observed from the foregoing that the month wheel is carried by the dial head in the sense that the major portion of the rotative movement of the month wheel is in the same direction as the dial head; but it will also be noted that each time that an arm of the star wheel 53 engages the stop pin 54, an angular motion is imparted to the month wheel which is backward with respect to the direction of rotation of the dial head, whereby the month wheel has an intermittent motion relatively to the dial head, which is retrogressive. The invention is not necessarily limited to this relative motion being retrogressive, because the relative motion might be in a forward direction.

Rotatably mounted on the hub 31, directly in back of the month wheel 46, is the cam assembly 61, comprising a sleeve 61a, an annular flange 61b radiating from this sleeve, and two cam discs 61c and 61d. The cam discs are mounted at opposite sides of the annular flange 61b, and are rigidly secured thereto by rivets 62 passing through the cams and through the flange. The month wheel 46 is secured to the cam sleeve 61a by screws 63 and pins 64, which are in such relation as to preclude the possibility of the month wheel being secured to the cam hub in any other than the proper angular relation. For example, referring to Figure 6, the screws 63 thread into tapped holes 63a in the end of the cam hub, and the two pins 64 project from the end of the cam hub in such relation to the screw holes as to be capable of reception in pin sockets in the month wheel only when the wheel and cam hub are in one predetermined angular relation. Thus, all possibility of erroneous assembly of these two parts is avoided. The end of cam hub 61a bears against the washer 66, which in turn bears against an annular shoulder 31b projecting from the inner portion of the main hub 31. It will be clear that the two cams 61c and 61d rotate in direct synchronism with the month wheel 46. The two cams are disposed between the two swinging arms 68 and 69, which carry the switch actuators 12 and 13. The arm 68 has a ring-like inner end which is secured to a hub or pinion ring 68a which is rotatably mounted on the cam hub 61a in rear of the cam disc 61c. Like-

wise, the swinging arm 69 has a ring-like inner end which is secured to a hub or pinion ring 69a, the latter being rotatably mounted on the cam hub forwardly of the front cam 61c. As shown in Figure 4, each pinion ring is preferably secured to its swinging arm by providing the ring with a reduced neck portion which is extended through the ring-like inner end of the arm and is then peened over on the outer side of the arm. The outer ends of the swinging arms are guided in their oscillating motion between pairs of arcuate guide bars 71, 72. The ends of the guide bars 71 are mounted on the two supporting posts 36 and 38, with suitable spacing washers interposed between the ends of said bars or plates, and the other two guide bars 72 have their ends mounted on the other two posts 37, 39 with suitable spacing washers intervening, these two sets of guide bars being offset fore and aft, as illustrated in Figure 4, corresponding to the fore and aft offset relation between the swinging arms 68 and 69. The guideways defined between each pair of these bars prevent any possibility of the swinging arms being bent by any force acting against the arms or against their switch actuators in a fore and aft direction, and insure that the two switch actuators 12 and 13 will always engage with their proper switch tripping arms 17 and 18.

As clearly shown in Figures 3 and 5, each of the rings 68a and 69a are provided with gear teeth 68b, 69b. These teeth need only extend over a limited portion of the periphery of each ring, although they might be extended around the entire ring, if desired. Coacting with these toothed portions are two cam followers 75, 76 which are approximately J-shaped. Both of these cam followers are pivotally mounted on the previously described pintle 43, which is disposed between the posts 36, 37. Mounted on these follower arms intermediate their ends are cam follower pins 75a, 76a, which are rigidly secured to their respective arms and which project laterally therefrom to ride upon the periphery of the associated cam. The two follower arms are disposed on the outer sides of their respective cams; the arm 75 being disposed between the cam 61d and the swinging arm 68 with its follower pin 75a projecting forwardly over the periphery of the cam 61d, and the arm 76 being disposed between the cam 61c and the swinging arm 69 with its follower pin 76a projecting rearwardly over the periphery of the cam 61c. The hub ends of the two cam followers have coil springs associated therewith tending to swing these followers inwardly so as to hold their follower pins 75a, 76a resiliently pressed against the peripheries of their respective cams. The spring 78 associated with the follower 76 is illustrated in Figure 3, this spring having one end hooked over the outer or back edge of the follower 75 and having the other end bearing against pin 79, which extends between the mounting plate 26 and the bridge bar 41. The other spring associated with the other cam follower is a duplicate thereof. The inwardly curved swinging end of each cam follower is provided with internal sector teeth which mesh with the pinion teeth of the associated swinging arms, Figure 3 illustrating these sector teeth 76b meshing with the gear teeth 69b, and it being understood that the other follower arm 75 has corresponding sector teeth 75b meshing with the pinion teeth 68b of its associated swinging arm. The pitch circle of these sector teeth has its axis at the pintle 43.

It will be seen from the foregoing that as the month wheel and cam discs are given their intermittent angular motion with respect to the continuously revolving dial head, the cam follower pins 78a, 78a are caused to swing inwardly and outwardly by the varying radii of the cams against which they are continuously pressed by the springs 78. This inward and outward movement of the cam followers is transmitted to the swinging arms 68, 69 through the external and internal gear sectors represented at 69b, 78b. Thus, the swinging arms and their switch actuators 12 and 13 are caused to swing to different angular positions relatively to the dial head, as represented by the full line and dotted line positions illustrated in Figure 3. The aforementioned object of securing a constant ratio of motion transmission is clearly obtained by the above described relation of pinions and gear sectors, since, irrespective of whether either cam follower is at the outward, intermediate or inward positions of swinging motion, it is still transmitting rotative movement to its associated swinging arm at the same ratio. Accordingly, the design of the cams 61d and 61c is simplified, inasmuch as no compensation need be included in these cams for any varying ratio of motion transmission between the cam follower and the switch actuator. The cam followers are always held pressed against the cams by the springs 78 because the direction of rotation and general arrangement are such that the pressure of either switch actuator against its associated switch lever reacts to cause the follower pin 78a, 78a to be pressed inwardly against its respective cam with increased pressure. Consequently, there is no possibility of play or relative motion which might cause error.

The outer ends of the swinging arms 68, 69 are provided with arcuate slots 81 which receive the switch actuators 12, 13, and enable the latter to be adjusted to different angular positions with respect to each of their swinging arms. The actuator 12 is illustrated in section in Figure 4, from which it will be seen that it comprises a head 12a abutting the back side of the swinging arms and including a neck portion 12b having flattened sides which can slide in the slot 81 but cannot rotate therein. A threaded shank 12c extends upwardly from this head and neck portion and receives a nut 12d having a reduced sleeve portion which abuts the outer side of the swinging arm. A roller 12e is rotatably mounted on this reduced sleeve portion of the nut, and constitutes a rotatable bearing surface for contacting with the associated switch arm 17. Releasing the nut 12d enables the actuator 12 to be shifted to any desired position in the slot 81, for advancing or retarding the time of switch actuation with respect to the position of the swinging arm 68. The other switch actuator 13 is similarly constructed and is similarly adjustable with respect to its swinging arm 69. Notches or other marks 82 may be provided adjacent to the slots 81 for indicating the different positions of adjustment of the switch actuators.

A bridge plate 84 is secured to the posts 36, 37 and is provided with a corresponding arcuate slot 81' for receiving either the "Off" switch actuator 13 or for receiving a switch actuator similar thereto. This bridge plate is disposed substantially in the same transverse plane as the swinging arm 69, so that any switch actuator mounted in the slot 81' of this bridge plate will be effective to engage the switch lever 18. The

purpose of this bridge plate is to provide for the adjustable mounting of a switch actuator which can be arranged so that it will always open the switch 14 at a selected hour around midnight, irrespective of seasonal change in the position of the "On" switch actuator 12, or of the "Off" switch actuator 13.

I claim:—

1. In time switch actuating mechanism, the combination of a time controlled rotary head, a swinging arm mounted on said head and movable relatively thereto, a switch actuator carried by said arm, a cam mounted on said head and rotatable relatively thereto, means for causing rotation of said cam relatively to said head, a J-shaped cam follower having its upper end pivotally mounted on said rotary head, a follower member projecting from an intermediate portion of said follower and engaging with the outer periphery of said cam, an internal gear sector with in the curved portion of said J-shaped cam follower, and a pinion meshing with said gear sector and operatively connected with said swinging arm.

2. In time switch actuating mechanism, the combination of a time controlled rotary head, a cam carried by said head and movable relatively thereto, means for causing movement of said cam relatively to said head, a cam follower cooperating with said cam, a swinging arm mounted on said head, means for transmitting motion from said cam follower to said swinging arm, a switch actuator carried by said swinging arm, and a guide bar fixedly secured to said rotary head and coacting with said swinging arm for guiding the swinging motion of the latter.

3. In time switch actuating mechanism, the combination of a time controlled rotary head, a cam carried by said head and movable relatively thereto, means for causing movement of said cam relatively to said head, a cam follower cooperating with said cam, a swinging arm mounted on said head, means for transmitting motion from said cam follower to said swinging arm, a switch actuator carried by said swinging arm, and a pair of spaced guide bars fixedly secured to said rotary head and defining therebetween a guideway through which the outer portion of said swinging arm extends.

4. In time switch actuating mechanism of the class described, the combination of a time controlled rotary dial head, a pair of switch actuating members movably supported on said dial head, a pair of cams rotatably mounted on said dial head, and mechanism for transmitting motion from said cams to said switch actuators, said mechanism comprising two cam followers pivotally mounted on the same pivot axis and operatively connected with said switch actuators.

5. In time switch actuating mechanism of the class described, the combination of a time controlled rotary dial head, a pair of switch actuators mounted on said head to rotate therewith and movable relatively to said head, a pair of cam followers pivotally mounted on said head, a pair of cam discs supported on said head to rotate therewith but being rotatable relatively to said head, said cam discs cooperating with said cam followers and being disposed in transverse planes between the transverse planes of said cam followers, means operatively connecting said cam followers with said switch actuators, and means for causing movement of said cam discs relatively to said dial head.

6. In time switch actuating mechanism of the class described, the combination of a time con-

trolled rotary dial head, a pair of cams carried by said dial head to rotate therewith, said cams being rotatable relatively to said dial head, means for causing rotative movement of said cams relatively 5 to said dial head, a pair of cam follower levers pivotally mounted on said dial head, one disposed forwardly of both of said cams and the other disposed rearwardly of both of said cams, said levers having projections riding on the peripheral surfaces of said cams, spring means for yieldingly holding said projections in engagement with said cams, a pair of swinging arms pivotally mounted on said dial head, one disposed forwardly of both cams and the forward cam follower lever and the 10 other disposed rearwardly of both cams and of the rearward cam follower lever, means for transmitting motion from said cam follower levers to said swinging arms, and switch actuators mounted on said swinging arms.

20 7. In time switch actuating mechanism of the class described, the combination of a time controlled rotary dial head comprising a mounting plate and a mounting hub extending axially therefrom, a month wheel rotatably supported on said 25 mounting hub, means for causing rotation of said month wheel relatively to said dial head, a pair of cams connected with said month wheel to rotate therewith, a pair of cam followers pivotally mounted on said head and cooperating with said 30 cams, a pair of switch actuators movably mounted on said head, means for transmitting motion from said cam followers to said switch actuators, a dial plate on the outer side of said mounting plate, said dial plate having designating indicia inscribed thereon, and means removably securing said dial plate to said mounting plate enabling said dial plate to be substituted by a different dial plate having different designating indicia thereon.

35 8. In time switch actuating mechanism, the combination of a time controlled rotary head, a switch actuator associated with said head and movable relatively thereto, a cam associated with said head and movable relatively thereto, said switch actuator and said cam being concentrically mounted with respect to each other, means for 40 causing movement of said cam relatively to said head, a pivot mounted on said head, a cam follower mounted on said pivot for pivotal movement with respect to said head and cooperating with said cam, and gear mechanism for directly transmitting a constant ratio of motion from said 45 cam follower to said switch actuator.

9. In time switch actuating mechanism, the combination of a time controlled rotary head, a movable member carried by said head and movable relatively thereto, a switch actuator carried by said movable member, a cam associated with 5 said head and rotatable relatively thereto, said movable member and said cam being concentrically mounted with respect to each other, means for causing motion of said cam relatively to said head, a pivot mounted on said head, a cam 10 follower mounted on said pivot for pivotal movement with respect to said head and cooperating with said cam, and cooperating gears carried by said head for directly transmitting a constant ratio of motion from said cam follower to said 15 movable member.

10. In time switch actuating mechanism, the combination of a time controlled rotary head, an arm mounted on said head for swinging motion relatively thereto, a switch actuator carried by 20 said arm, a cam carried by said head and rotatable relatively thereto about the axis of said head, said arm and said cam being concentrically mounted with respect to each other, means for causing rotative movement of such cam relative- 25 ly to said head, a cam follower cooperating with said cam, and mechanism including a cooperating pinion and sector directly carried by said arm and said cam follower respectively for directly transmitting a constant ratio of motion from said 30 cam follower to said arm.

11. In time switch actuating mechanism of the class described, the combination of a time controlled rotary dial head, two swinging arms carried by said head and movable relatively thereto, switch actuators carried by each of said swinging arms, two cams mounted on said head and rotatable relatively thereto, said arms and said cams all being concentrically mounted with respect to each other, means for causing rotation 40 of said cams relatively to said head, a single pivot mounted on said head, a pair of cam followers mounted upon said single pivot for pivotal movement with respect to said head, means yieldingly urging said cam followers into cooperation with 45 said cams, gear sectors directly carried by said cam followers, and pinions meshing with said gear sectors and directly carried by said swinging arms for directly actuating said arms at a constant ratio of movement.

50

FREDERICK C. HOLTZ.
